Marlin W. Wessendorf

UNITED STATES PATENT OFFICE.

MARTIN W. WESSENDORF, OF BUCHANAN, MICHIGAN.

DOORKNOB.

Application filed April 27, 1923. Serial No. 634,998.

To all whom it may concern:

Be it known that I, MARTIN W. WESSENDORF, a citizen of the United States, residing at Buchanan, in the county of Berrien and State of Michigan, have invented certain new and useful Improvements in a Door-knob, of which the following is a specification.

This invention relates to improvements in door knob attachments, and more particularly to a device for securing the door knob to the latch shaft without the usual fastening screw.

The primary object of the invention is to provide a structure by which the door knob may be secured to the shaft and be firmly held so that the knob cannot work loose from its position on the shaft.

Another object of the invention is to provide a structure of this character which may be easily disconnected when the knob is to be removed.

Other objects of the invention will appear upon consideration of the following detailed description and drawings, wherein:

Figure 1 is a side elevation of the device constructed in accordance with my invention.

Figure 2 is a detailed view thereof showing the same partly disassembled.

Figure 3 is a longitudinal section through the device showing the parts assembled.

Referring to the drawings by numerals, the usual shaft 1 extends from the latch in the usual manner and is provided with a series of apertures 3. The hollow shank 4 of the knob 5 is adapted to fit over the outer end of the shaft 1 and, in the present instance, the end of the portion 4 is provided with exterior screwthreads, thus forming a screwthreaded sleeve adapted to fit over the shaft 1. This screwthreaded sleeve is provided with a transverse opening 5' which is adapted to register with any of the openings 3 and receive a locking pin 6 which extends transversely through the opening, as is shown in Figure 3, thus holding the shank 4 of the knob on the shank 1. The retaining ring 7 is provided with interior screwthreads and is adapted to be screwed on the free end of the screwthreaded sleeve and cover the ends of the opening 5', thus main-

taining the locking pin 6 in position against accidental or casual displacement. The locking ring 8 is provided with screw threads and fits over the opposite end of the sleeve and is locked against the retaining ring 7 so that the two rings will be held tightly against each other and against the flange plate on the latch mechanism.

In this manner the knob is firmly held to the shank 1 by the locking pin 6 and since the locking pin is entirely covered by the ring 7, it will be impossible to have the pin accidentally displaced as so often happens in the type of fastening in use at present.

The ring 7 may be moved longitudinally upon the shank 4 of the door knob 5, so that said ring 7 engages the door in order to take up loose play, which is caused due to wear, and the locking ring 8 adjusted against the ring 7 to bind and hold the ring 7 in adjusted position.

Minor changes may be made in the details of construction without departing from the spirit of the invention or the scope of the claim hereunto appended.

What I claim is:

A knob attaching device comprising in combination with a noncircular shaft having openings passing transversely therethrough, a shank adapted to fit snugly over the shaft and having openings adapted to register with the openings in the shaft, a pin passing transversely through one of the openings in the shaft and having its end portion received in the openings of the shank, the shank being screw threaded exteriorly from one end and to a point between its ends and beyond the openings in the shank, a retaining ring internally threaded and adapted to engage the thread upon the shank and extend over the openings of the shank and with one end edge disposed at the end of the shank and a locking ring internally threaded and engaging the thread of the shank and adapted to engage at its edge against the inner edge of the retaining ring.

In testimony whereof, I have affixed my signature.

MARTIN W. WESSENDORF.
